HERMAN F. HOEVEL, OF NEW YORK, N. Y.

AIR TANK.

Application filed January 14, 1922. Serial No. 529,164.

My invention relates to air-tanks, particularly of the type in which the air is employed to carry fine material, such as sand, from the tank through suitable piping to nozzles for projecting such material against objects to be treated therewith. Tanks of this type have been made to receive the sand or other fine material through an opening closed at times by a valve, under the influence of the compressed air, while at other times this valve is allowed to open, to cause the material stored above the valve, to pass into the tank. Air-tanks of this character, as made hitherto, have had certain drawbacks owing to the fact that the movement or stroke of the valve had to be rather small, thus also restricting the size of the opening through which the stored material passed downwardly into the tank. On account of this, the transfer of such material into the tank through the valve opening was rather slow.

The object of my present invention is to overcome this difficulty and to provide a construction allowing the valve to move to a relatively considerable distance from its seat so as to afford a comparatively wide opening for the passage of the sand or other material into the tank. The subsequent closing of this valve is obtained by the pressure of the air acting on said valve either directly or through an element operatively connected therewith, in such a manner that the compressed air will move the valve toward the closed position before such air enters the tank proper.

I will now describe four satisfactory and preferred embodiments of this invention, and the scope of the invention will then be indicated in the appended claim.

Reference is to be had to the accompanying drawings, in which Fig. 1 is a vertical section of one form of air-tank constructed according to my invention, and Figs. 2, 3 and 4 are partial vertical sections illustrating three additional forms of my present invention.

In Fig. 1, 10 indicates the body or shell of the air-tank, with a top or partition 11 having a central opening to which is fitted a plate or ring 12, formed with an opening 13 through which the sand or other material may pass into the chamber 14 of the tank. This opening preferably contains a sleeve or lining 15, the lower portion of which is surrounded by a gasket 16, held in

position by a securing ring 17. The lower face of the gasket 16 forms an annular seat for the upper edge of the cylindrical flange 18 on the valve body or disk 19, said disk being formed with a central upwardly-extending boss or socket 20 fitted over a stationary vertical pin or rod 21. This rod may be secured to the central portion of a disk or plate 22 supported, by means of brackets 23, from the ring 17. A spring 24 coiled around the rod 21, is employed to partly or entirely counterbalance the weight of the valve and of the parts connected therewith, said spring generally not being intended to be of sufficient strength to close the valve.

The disk or plate 22 is provided with a cylindrical upward extension or casing 25 around which is adapted to fit a cylindrical flange 26 extended downwardly from the valve body or disk 19. When said flange 26 is thus fitted around the cylinder or extension 25, a substantially closed chamber 27 is formed by the parts 19, 20, 22, 25, and 26; however, the flange 26 need not fit air-tight around the extension 25. Into this chamber 27 compressed air or other fluid under pressure is conveyed by a pipe 28, which may be branched from a pipe 29 receiving compressed air from any suitable source. This pipe 29 may also supply the air for carrying the sand or other material from the chamber 14 to the nozzles or other place of use. In Fig. 1 I have indicated an outlet opening 30 in the bottom 21 of the chamber 14, the connection of said opening with the pipe 29 being controlled by a cock 32.

The height of the flange 26 is such that when the flange 18 of the valve is seated upon the gasket 16, the lower edge of the flange 26 will be above the upper edge of the extension 25, thus affording a wide opening for the passage of air from the chamber 27 into the chamber 14.

The operation is as follows: When the valve is open, as indicated by full lines in Fig. 1, the sand or other material resting on the partition 11 and on the upper surface of the valve disk, will be allowed to pass into the chamber 14 through the relatively wide opening existing in this position of the valve, so that the transfer of such material into the chamber 14 from above will take but little time. The valve is caused to open by establishing a condition in which the air pressures above and below the partition 11

will be substantially equal. For instance, if the storage space above the partition 11 is open to the surrounding air, the valve will be caused to open when the pressure in the chamber 14 is reduced to atmospheric pressure, as by shutting off the supply of compressed air to such chamber. As soon as substantially equal pressures exist above and below the partition 11, the weight of the sand or other material resting on the valve, and in most cases, the mere weight of the valve, will open the latter quickly, since, as stated above, the spring 24 is not strong enough to keep the valve closed, but is intended simply to counterbalance the weight of the valve partly or entirely. When compressed air is then admitted through the branch pipe 28 into the chamber 27, such air will first lift the valve, the latter moving after the manner of a piston (even if there is no air-tight fit) until the lower edge of the flange 26 clears the upper edge of the stationary extension 25. As soon as this occurs, the chambers 14 and 27 will communicate freely at the upper end of the latter, and the entire chamber 14 will thus be filled with air at the same pressure as the pipes 28, 29. At the same time, under the influence of the current of air seeking to escape through the opening 13, the valve will continue its upward movement until the flange 18 becomes seated on the washer 16, thus closing said opening 13. The dotted lines in Fig. 1 indicate the closed position of the valve. Then, as long as conditions remain unchanged, the valve will be kept closed by the pressure of air in the chamber 14, and no sand or other material will pass into said chamber until the valve is caused to open again by restoring a condition of equal pressures on both sides of the valve.

The construction shown in Fig. 1, in which the valve has a flange 26 fitted around the stationary extension or cylinder 25, has the advantage that the valve covers such cylinder, and prevents the accidental passing of sand or other substance into the chamber 27. However, my invention is not restricted to this arrangement, and other embodiments are illustrated by Figs. 2, 3, and 4.

According to Fig. 2, the flange 26' extending downwardly from the valve disk or valve body 19 is not in line with the upwardly-projecting flange 18, but is made of smaller diameter, so as to fit into the cylinder or casing 25 instead of around the same. At the lower end of the flange 26', I have shown a plate 34, having openings 35 and engaged by the upper end of the coiled spring 24. The main purpose of this plate 34 is to enable me to use a shorter spring 24; however, this plate might be omitted and the spring made long enough to engage the valve disk 19 as in Fig. 1. In the open position of the valve, Fig. 2, the flange 26' covers openings 33 in

the cylinder 25. Thus, when compressed air enters the chamber 27 from the pipe 28, the valve will be raised, and before the valve becomes seated on the gasket 16, the lower edge of the flange 26' will uncover the lower portions of the openings 33, thus establishing free communication between the chambers 27 and 14, with the same effect as in the construction illustrated by Fig. 1. It will be understood that when the valve is seated, the openings 33 will be uncovered fully, the lower edge of the flange 26' being either flush with the upper edge of said openings, or at a higher level. Here too, a tight fit between the flange 26' and the cylinder 25 is not essential.

In the construction shown in Fig. 3, I employ a piston-like plate 36 in substantially the same position as the plate 34 of Fig. 2, but the plate 36 is imperforate and thus forms the upper wall of the chamber 27. The plate 36 is connected with the valve body 19 by a sleeve 37 fitted around the pin 21 and forming, if desired, a continuation of the boss or socket 20. The operation of this form of my invention will be practically the same as in the case of Fig. 2. The boss 20 and the pin 21 guide, or help to guide, the valve in its vertical movement; this is of particular importance in the construction Fig. 1, in which, when near the seating position, the valve can no longer be guided by the cylinder 25, since the flange 26 clears said cylinder. In Figs. 2 and 3, the cylinder 25 always remains in engagement with a portion of the valve structure, or at least close enough thereto to hold the valve against material lateral movement.

While Figs. 1, 2, and 3 show constructions in which the valve 18, 19 is above the compressed-air chamber 27, Fig. 4 illustrates an arrangement in which the relation of these parts is reversed. In this construction, a stem or rod 38, secured to the valve body 19, extends upwardly from the center of this body to a plate or piston 39 forming the upper wall of the chamber 27' within the cylinder or casing 25', the latter being located above the partition 11 and supported from the plate 12 by brackets 23' or otherwise. Compressed air is supplied to the chamber 27' by a pipe 28 as before. As the valve approaches its seating position, the piston 39 will progressively uncover one or more openings 33' in the wall of the cylinder 25', and compressed air will then pass from the chamber 27' through said opening or openings 33' and through a pipe or pipes 40 into the chamber 14; that is to say, the chambers 27' and 14 will communicate freely when the piston 39 is above the opening 33'. A suitable packing 41 is indicated where the rod 38 passes through the bottom 22' of the cylinder 25'; and a spring 24' serves to counterbalance partly or entirely the weight

of the valve and of the parts moving in unison therewith. It is thought the operation of this form of my invention will be readily understood without any further detailed explanation. In Fig. 4, the cylinder 25' will remain in guiding engagement with a portion (39) of the valve structure throughout the movement of the valve. An air-tight fit of the piston within the cylinder is required in the construction illustrated by Fig. 4.

By having an enlargement or casing such as 25 or 25' connected with the pipe 28, I secure the important advantage that the pressure fluid will act on the comparatively large surface of the plate 19, 36, or 39, thus causing the valve 18, 19 to close more rapidly and with greater force than if the end of said pipe 28 (without any casing or enlargement) discharged directly against such plate 19, 36, or 39.

Various modifications may be made without departing from the nature of my invention as set forth in the appended claims. The balancing spring 24 or 24' might be omitted. In the constructions illustrated by Figs. 1, 2, and 3, I should generally prefer to have the flange 26 or 26' or the plate 36 fit the cylinder 25 loosely, to secure easier play of the valve. If there was a small permanently-open by-pass connection from the pipe 28 to the interior of the tank, this would be within the scope of my invention, since the operation of the valve relatively to the opening 13 and to the casing or cylinder 25

or 25' would remain practically the same as without such by-pass connection.

In each of the constructions illustrated herein, the casing which defines the chamber 27 or 27' is an apertured casing. In the form shown in Fig. 1, said casing has a single aperture, constituted by the open end of the cup-shaped casing; in the forms shown in Figs. 2, 3, and 4, the casing has a plurality of apertures 33 or 33'. It will be obvious that the open end of the casing shown in Fig. 1, and the plurality of apertures in Figs. 2, 3, and 4, are full equivalents of each other.

I claim:—

A tank provided with an opening for the entrance of a charge of material, an inwardly-opening valve for closing said opening, an open ended casing having a cross sectional area approximately equal to the area of said valve; a conduit connecting said casing with a source of fluid under pressure, and a flange extending from said valve toward said casing and of such length as to stand clear of the casing when the valve is seated, so as to establish free communication between the casing and the interior of the tank, said flange fitting the said casing when the valve is fully open, to interrupt the free communication of said casing with the interior of the tank.

In testimony whereof I have signed this specification.

HERMAN F. HOEVEL.
